CLAIM

The ornamental design for a swim board for carrying scuba diving equipment, as shown and described.

DESCRIPTION

FIG. 1 is a top perspective view of a swim board for carrying scuba diving equipment showing my new design;

FIG. 2 is a top plan view thereof with an air tank, the broken lines are for illustrative purposes only and form no part of the claimed design;

FIG. 3 is a bottom plan view thereof; and,

FIG. 4 is a rear elevational view thereof, the broken lines are for illustrative purposes only.

FIG. 1

FIG. 2
